UNITED STATES PATENT OFFICE.

CHESTER M. BATES, OF ELVERSON, PENNSYLVANIA, ASSIGNOR, BY MESNE ASSIGNMENTS, TO LIVINGOOD MANUFACTURING CORPORATION, OF LEBANON, PENNSYLVANIA, A CORPORATION OF PENNSYLVANIA.

FOLDING STOVE.

Application filed April 21, 1922. Serial No. 555,812.

To all whom it may concern:

Be it known that I, CHESTER M. BATES, a citizen of the United States, residing in Elverson, Chester County, Pennsylvania, 5 have invented Folding Stoves, of which the following is a specification.

This invention relates to folding stoves adapted particularly for camping purposes, the object of the invention being to provide 10 a compact, strong and efficient stove of this nature having certain novel and improving features, as hereinafter fully set forth.

In the attached drawings:

Figure 1, is a view in perspective of a 15 stove made in accordance with my invention;

Fig. 2, is a longitudinal section of the stove;

Fig. 3, is a section on the line 3—3, Fig. 2; 20 Figs. 4 and 5, are fragmentary sections illustrating details of the construction;

Fig. 6, is a longitudinal section of the stove folded;

Fig. 7, is a section on the line 7—7, Fig. 6, 25 and

Figs. 8 and 9, are views in perspective of one of the stove accessories.

With reference to the drawings, the stove comprises in the present instance a rectangular open top base portion 1, near the upper edge of each side of which is hinged a plate which, when elevated, is adapted to constitute in effect an extension of that side of the base member to which it is hinged. As 30 best shown in Figs. 2 and 3, these plates, which are designated by the numerals 6, 7, 8 and 9, respectively, and are attached respectively to the front wall 2, the rear wall 3, and the side walls 4 and 5 of the base, are 35 hinged to their respective side walls on the inside of the latter and on a line somewhat below the top edges of the said sides, whereby when the sides are elevated, as shown in the aforesaid Figures 2 and 3, a tight joint 40 is made by reason of the said plates bearing against the inner faces of the sides of the base, as shown in the fragmentary section of Fig. 5.

As shown in Figs. 2 and 4, the side plates 50 are provided in each of the upper corners with a suitable projection 10, and the front and rear edges of the said side plates are turned inwardly in such manner as to form an abutment for the front and rear plates

6 and 7, the front and rear plates 6 and 7 being adapted to occupy the space between the extensions 10 and the said inturned edges 11 of the side plates, in the manner best shown in Fig. 4, whereby both the side, front and rear plates are supported in the upright position and substantially tight joints made at the corners by reason of the abutment of the front and rear plates against the said inturned edges 11 of the side plates. An integral cover plate 12 is provided, having 60 down-turned flanges at the edges, which fits over the tops of the elevated plates and constitutes the top wall of the fire-box.

As shown in Fig. 1, the front wall 2 of the base portion 1 and the front plate 6 is 70 each provided with a hinged door, 13 and 14, respectively, said doors being equipped in the usual manner with suitable latches 13^a and 14^a, whereby they may be held closed. There is also provided within the interior of 75 the base portion 1 a grate member 15, said member in the present instance consisting of a perforated plate supported on legs 16, 16, which rest in the bottom of the base and support the perforated plate somewhat below the top edges of the base portion. As best shown in Figs. 3 and 7, these legs 16 lie close to the side walls 4 and 5 of the base portion, they being so placed as not to obstruct the interior of the latter. As shown 80 in Figs. 2 and 6, the cover 12 is provided at its rear with a flue opening 17, in which is secured a nipple 18 adapted to receive an end of a flue pipe 19.

The operation of the stove in so far as 90 described will be apparent. Fuel, usually wood, will be fed into the stove through the door 13, the door 14 constituting the draft door which, when open, permits air to pass into the lower part of the base 1, upwardly 95 through the perforated plate which constitutes the grate, and through the fuel-bed to the flue 19.

The manner in which the stove is folded is best illustrated in Figs. 6 and 7. The 100 cover 12 is first removed, and the side plates 8 and 9 then sprung outwardly sufficient to release the sides of the front and rear plates 6 and 7 and to permit their being folded down to a substantially horizontal position, 105 as shown in Fig. 6, the side plates then being folded downwardly on top of the front and back plates, as shown in Fig. 7. The cover

plate 12 is adapted to fit over the top of the base member 1, which converts the said base member into a closed case. As clearly shown in the drawings, a handle 20 is attached to 5 one side of the base element so that the entire folded structure may be carried in the manner of the ordinary suit case.

In Figs. 1 and 2, I have illustrated, in addition to the hereinbefore described structure, an oven drum which may be inserted 10 in the flue pipe, said drum comprising outer and inner spaced walls 21 and 22, and the space between the walls communicating by means of nipples 23, 23, at top and bottom 15 with the flue pipe 19, the latter in this case being sectional and fitting around the nipples 23, 23, as clearly shown in Fig. 2. The interior of the drum is closed by a rear wall 24 and by a hinged door 25 at the front, 20 said door being provided with the usual latch 25^a. A rack 26 is provided in the interior of the drum which is suitably supported therein and constitutes a rest for 25 pans or other receptacles. The heated gases rising through the flue 19 pass between the double walls of the cylinder, which is thus made to constitute an oven for baking purposes.

There may also be provided receptacles 30 and 28 for water or other liquids, and for the sake of compactness, these receptacles may be recessed in the flat rear walls thereof, as shown in Figs. 8 and 9, so that they may fit closely around the flue pipe 19, 35 the receptacle 27 being provided with a strap 29 which is adapted to encircle the flue pipe whereby this receptacle is retained on the rear of the stove, as shown in Fig. 1. There may also be provided a spigot 30, through 40 which the liquid may be drawn from the receptacle.

As shown in Figs. 1 and 3, a rack 31 which is adapted to be secured at one side of the stove in such manner as to constitute an 45 extension of the upper surface of the cover may be employed, the rack in the present instance being supported by hooks 32, 32, on the inner edge which fit into straps 33 on the cover, and by means further of trusses

34 whose ends fit in straps 35 and 36 respectively on the side plate 9 and on the under side of the rack. This rack, together with the flue pipe 19 and the receptacles 26 and 27, may be so proportioned as to fit within the interior of the folded stove in the space 55 beneath the grate element 15.

The construction as described is of great simplicity, extremely strong, and efficient in 60 operation.

I claim:

1. In a folding stove, the combination with a plate having flanges at the side edges and constituting a shallow receptacle, of plates hinged to the flanges inside the outer edges of the latter and when extended forming extensions of the flanges, and a member adapted for attachment both to the outer edges of the extended plates to form a wall of the stove, and to the edges of the flanges when the plates are turned inwardly to constitute a cover for the receptacle confining the contents. 65

2. In a folding stove, the combination with a base comprising a bottom plate having upward flanges at the edges, of plates hinged to the flanges below the upper edges, and when elevated forming extensions of the flanges and the side walls of the stove, and a plate adapted for attachment both at the top of the said side plates to form the top 75 of the stove, and at the top of the said flanges to enclose the base and confine the contents thereof. 80

3. A folding stove comprising an open-top base member, plates hinged to the side walls of said base member and adapted to be folded up to form upward extensions of the side walls to which they are attached, a cover plate adapted to rest over the tops of said plates, said cover plate having at one 90 end thereof a flue opening, a flue pipe communicating with said opening and detachable from the cover, and a receptacle comprising a vertical recess for the flue pipe and a strap attached at the side edges of 95 the recess and adapted to encircle the flue pipe to secure the receptacle thereto.

CHESTER M. BATES.
